UNITED STATES PATENT OFFICE.

HERBERT E. SMITH, OF SPOKANE, WASHINGTON.

MAIL-EXCHANGING DEVICE.

1,312,059.

Specification of Letters Patent.

Patented Aug. 5, 1919.

Application filed August 29, 1916. Serial No. 117,447.

To all whom it may concern:

Be it known that I, HERBERT E. SMITH, a citizen of the United States, residing at Spokane, in the county of Spokane and State 5 of Washington, have invented certain new and useful Improvements in Mail-Exchanging Devices, of which the following is a specification.

My invention relates to improvements in 10 mail exchanging devices for the transferrence of mail from a moving train to a receiving and delivery station or from such station to a moving train.

One object of my invention is the provision of a device or apparatus of the foregoing character by means of which general mail matter, including parcel post matter, can be safely transferred from a moving train, traveling at high speed, to a station, 20 or vice versa, without danger of injury to the operators, the contents of the mail bags or pouches, or to the exchanging apparatus itself.

A further and most important object of 25 my invention is the provision of an apparatus to effect the foregoing exchanges, which also includes in its organization means by which both of the said operations—the transference from the train to the station 30 and from the station to the train—may be performed practically simultaneously; that is, a mail car equipped with my apparatus, in passing a station will not only take up the mail from the station, but will also, at 35 substantially the same instant, serve to transfer other mail to the station.

A still further object of my invention resides in the provision of a station apparatus so constructed and operated that it will not 40 be in danger of damage or destruction should a mail pouch suspended thereon and intended to be caught by a train passing in one direction, be engaged by the apparatus upon a train proceeding in the opposite direction,

45 Broadly, my invention comprises co-acting car and station apparatus of substantially similar parts, construction, and operation, each apparatus consisting of pivoted swinging horizontal arms, devices carried 50 by the arms for "catching" and for support-

ing the mail pouches, buffer or cushioning mechanism for absorbing the shock resulting from the impact of the catching devices, and mechanism for controlling the movement of the said arms.

Further than this my invention consists 55 of the novel features of construction, arrangement, and combination of parts to be hereinafter fully described and claimed.

For the purpose of convenience I will, 60 throughout the specification, refer to the apparatus carried by the mail car as the "car apparatus", and to the coacting corresponding station devices and mechanism as the "station apparatus".

65 In the accompanying drawings:

Figure 1 is a perspective view showing a mail car equipped with my apparatus in operative position as it would appear when about to pass (in the direction indicated by 70 the arrow) a station, with the equipment of the latter also in operative coactive position, and with a mail bag held in readiness by each apparatus for and substantially at the instant of engagement by the catching devices.

Fig. 2 is a top plan view showing the shock absorbing and arm controlling mechanism which is preferably mounted beneath the car floor, the solid lines indicating the 80 relative positions of the parts when the catching arms are swung out of operative position, and the dash lines indicating their relative positions when the said arms are in active or operative position.

Fig. 3 shows the shock absorbing and arm controlling mechanism and one of the catching arms, the view being a side elevation thereof.

Figs. 4 and 5 are enlarged detail views 90 of the station mail bag holding devices.

Fig. 6 is a side view in elevation of the station apparatus with the arms swung inwardly.

Fig. 7 shows the station apparatus as 95 viewed from the direction of the railroad track, the arms being in the position they would assume after the mail bags had been caught by a passing car apparatus.

Fig. 8 is an enlarged detail view in section 100

of one of the revoluble stub shafts which support the arm carrying standards for the car apparatus.

Fig. 9 is an enlarged detail view of the 5 upright shaft, housing therefor, and an operating lever, by means of which the catching arms on the car may be thrown into and out of operative position.

Figs. 10 and 11 are enlarged sectional 10 tail views showing the hook members carried by the car apparatus arms for suspending the mail bags to be delivered to the station apparatus.

Fig. 12 is a detail in section through the 15 jamb of the mail car doorway, showing the pivoted upper retaining means for the arm carrying standard.

I will first proceed to describe, in connection with the said drawings, the parts 20 and functions of the car apparatus, like reference characters being used throughout the specification to indicate like parts where they occur in the several views.

The numeral 1 designates an upright arm 25 carrying standard whose ends are provided with rectangular sockets 1^a to fit over the squared ends 2^a of the vertically disposed stub shafts 2 which are revolubly mounted in and extend entirely through (Fig. 8) the 30 base beam of the car and are positioned within the doorway thereof. By reason of the said sockets 1^a the standard 1 is available for engaging the squared ends 2^a of the shafts 2 so as to make the said standard interchangeable for use on either side of the 35 doorway.

It will be observed in Figs. 2 and 3 that upon the lower end of one of the said stub shafts 2 is mounted a segmental gear 3 which 40 meshes with a similar segmental gear 4 mounted upon a shaft 5 which shaft extends (Fig. 9) vertically within the car just inside the doorway and is provided with a suitable housing 6 and, at its upper end, a 45 pivoted manually operated lever 7. Referring to Fig. 2 it will be seen that the said segmental gear 4 is provided with an extended plate 8 having a mounting 9 upon which is secured a lever 10 connected by a 50 bar 11 with a lever 12 which latter is mounted upon the lower end of the remaining stub shaft 2 disposed in the doorway of the car upon the opposite side thereof as shown and revolubly mounted in the car base beam 55 in the same manner as its corresponding stub shaft heretofore described.

The said gears and levers which connect the two stub shafts in the manner stated 60 serve to rotate the said shafts simultaneously and exactly the same amount but in opposite directions of rotation. Thus it will be apparent that there is provided a movement for throwing the mail holding and catching arms 13, which are carried by 65 the standard 1, outwardly into operative po-

sition and for returning them in the proper direction, whether the said standard is mounted upon one side of the doorway or the other. It is to be understood that in all cases the standard is to be mounted on the 70 forward side of the doorway with respect to the head of the train when the train is traveling in a forward direction.

Still referring to the mechanism disposed below the car floor, pivotally attached to the 75 said lever 12 is the piston connecting rod 14 working in the cylinder 15 which is pivotally mounted at 16 to provide the necessary reciprocating motion. This arrangement serves as an air check or cushioning device 80 to absorb the shock incident to catching mail matter while the train is traveling at high speed, the initial movement due to impact being quite rapid and compressing the air within the cylinder from which the air is 85 allowed to leak slowly out through the leak or outlet valve 17 in the cylinder wall. The said cylinder is also provided with a check valve 18 to allow air to enter the cylinder chamber when the apparatus is being "set," 90 so as to avoid too much drag or resistance during the operation. The valve 17 which will "bleed" the air, due to compression, is provided with a suitable adjusting means which may be regulated to control the escape 95 of air from the cylinder.

To the plate 8 heretofore mentioned (Fig. 2) is attached one end of a spring 19; the other end of the spring being secured to the fixed stud or retaining member 20'. Immediately following the impact due to a mail 100 catching operation this spring will exert a pull or tension to aid the piston to exhaust the air from the said cylinder 15, and at the same time serve to maintain the catcher arms 105 13 within the recess of the doorway. When the said arms are extended out from the car, the position of this spring will be substantially that shown in dash lines in Fig. 2. The spring in the latter case will serve to 110 maintain the said arms in an outward position, it being slightly drawn past a dead center; but as the tension is considerable a slight movement of the arms will, through the standard 1 and the stub shaft 2, throw 115 the spring into a working position so that it will draw the arms within the doorway.

The working combination or co-action between the said cylinder check and the spring should be here noted. As the arms catch a 120 sack at a high rate of speed they are naturally thrown inwardly toward the door opening by reason of the sudden impact. As soon as the pressure within the cylinder balances the active pressure of impact the arms will be 125 brought to a stop and will then be subject to a slight re-coil motion, due to compression and resistance of the air in the cylinder. To overcome this re-coil the spring 19 will act against the stress of the re-coil to main- 130

tain the plunger against the air pressure in the cylinder, and the continued steady pull of the spring thereafter will serve to expel the air, allowing the arms to resume and 5 retain position within the doorway recess.

As will be seen, the arms 13—two being mounted upon the standard 1—extend at right angles from the standard which is revoluble by reason of the hereinbefore described stub shafts 2 and the pivoted upper support members 20, an enlarged sectional detail view of the latter members being shown in Fig. 12. By having this upper member or ring 20 pivotally mounted as shown, when the standard is raised for disengagement from the stub shafts it may be swung outwardly to allow the standard to drop down and disengage from the said upper support member.

20 The arms 13 are provided at their free ends with the bag engaging hooks 21 and extensions 22 upon which latter are mounted bag supporting and suspending devices 23. These latter devices together will support 25 the mail bag to be delivered to the station apparatus, which will be hereinafter described.

The supporting devices 23 are shown in detail in Figs. 10 and 11, each consisting of 30 a plate member 24 having forked ends 25 and a recess 26 for retaining a spring 27. The mail sacks adapted for use in connection with these supporting devices are provided at either end thereof with flexible members 35 or cords 28 extending therefrom and having attached to their free ends conically shaped buffer members 29.

In supporting the sacks or bags upon the holding or supporting devices 23 upon the 40 extensions 22 of the arms 13, the cords are placed between the forked ends 25 and are retained by reason of the springs 27 from disengagement except on lateral impact, when the springs will open far enough to 45 allow for the passage of the cords therethrough when the arms of the station apparatus have engaged the cords at either end of the bag.

The station supporting structure is preferably built up of tubular sections or members 30 and is provided with a platform 31 for the use of the operator, suitable steps 32 allowing of easy access thereto.

Upon the horizontal topmost tubular section 55 of the said structure are fixedly mounted by means of set screws 33 the upstanding arms 34 which support a shaft 35 upon which is pivoted at 36 the upper pouch supporting arm 37 of the station apparatus. The longer portion of this arm carries a bag 60 supporting and suspending means 38, a detailed view of which is shown in Figs. 4 and 5. The opposite or shorter portion is provided with a weight 39 which serves to 65 maintain the arm in an upright position

when not supporting a bag or pouch. The under member of the bag supporting means consists of the spreader arms 40 having their free ends pivoted to the station structure at 41, the arms converging to meet at 42 and 70 having secured thereto the bag holding means 43 which is similar to the bag holding means 38. While the latter means serves to support the bag and suspend the same, the member 43 steadies and prevents any 75 swinging movement of the bag and retains the flexible depending member or cord in taut vertical position ready to be grasped by the car catching devices.

When the said devices are relieved of the pouch it is evident that the upper supporting arm 37, by reason of the pivoted weighted arrangement described, will assume the position shown in Fig. 6 (solid lines), and that the spreader arm device will drop 85 down out of the way.

The upright standard 44, the equivalent of the standard 1 of the car apparatus, is shown as revolubly mounted in the fittings 45 and 46 (Fig. 7) and adapted to support 90 the bag catching arms 47 having the double bag engaging hooks 48, the said arms being arranged to swing in either direction, the controlling mechanism located below the station platform being designed to permit 95 of such movement so that the catching hooks carried thereby—there being two such hooks for each arm—will catch the mail bags from a train passing in either direction.

The said controlling mechanism (which 100 serves substantially the same purpose as the corresponding mechanism in the car apparatus) consists of the compression cylinder 49 pivotally mounted upon the depending member 50 which is secured to the station 105 platform toward the rear thereof, said member 50 having attached thereto one end of the spring 51, the other end being secured to the lower arm of the U-shaped cylinder supporting device 52, which latter is fixedly 110 mounted at one end upon the lower end of the said standard 44, the piston connecting rod 53 of the cylinder 49 being pivotally mounted on the bolt 54 which is positioned between the upper and lower arms of the said 115 U-shaped device 52, all as clearly shown in Figs. 6 and 7. The said cylinder is provided with an adjustable leak or outlet valve 55.

From the foregoing description, it is evident 120 that the pivoted method of mounting the said shock absorbing air compression cylinder will permit of the necessary movement thereof to compensate for the outward swinging movement of the U-shaped device 125 52, which movement takes place when the catching arms on the standard 44 are swung into their operative pouch catching position; while it is evident that the spring 51 will serve substantially the same purpose as the 130

corresponding spring of the car apparatus, overcoming the stress of the recoil of the cylinder piston, and returning the arms to their inoperative position.

5 I desire to here call attention to an important feature or advantage resulting from the particular arrangement of the catching arms and the upper bag supporting arm of the station apparatus, referring especially 10 to Figs. 6 and 7. It will be noted that the upper end 56 of the upright standard 44 is somewhat concave or hollowed out and that the tubular upper supporting arm 37—when the latter is in its bag supporting position (dash lines Fig. 6)—rests upon the said concave end so that the latter supports the former in substantially horizontal position when a pouch is suspended thereon.

Now, assuming that the catcher arms on 20 the standard 44 are in their catching position, at which time the extended catcher arms are set at an exact balance under tension of the spring 51 of the mechanism below the platform, it will be apparent that 25 the weight of a filled mail pouch held by the said supporting arm resting upon the said standard 44 will serve to steady and retain the said catcher arms in their outstanding active position and prevent movement 30 thereof in either direction due to wind pressure or a nominal unintended blow, which movement would, were it not for this preventive, throw the said arms off their balance and allow the said spring to pull the arms 35 into their inactive position. It will thus be seen that the weight of the sack or pouch pulling down on the arm 37 steadies the bag catching arms 47, and at the same time provides means for limiting the downward 40 movement of the arm 37 as the same will be supported horizontally by the concave end of the standard 44, so that such arrangement serves a double purpose.

From the foregoing description and explanation of the car and station apparatus, it is apparent that I have provided a means for each apparatus which will support a bag in such a manner that wind pressure against the suspended bag, which is a 50 serious consideration as to the car apparatus, will not and cannot dislodge the same from the apparatus. On the other hand the bag is so supported that when it is engaged it will be instantly released without resistance and 55 without the imposition of injurious strain upon the bag. That by supporting the bag in a substantially vertical position by means of the vertical extending cords, lines, or chains projecting endwise from the bag, any 60 movement imparted to the bag will be of a rotary whirling character and will not involve bodily swinging movement thereof.

The suspended bag will be held accurately in such a manner as to insure registry of its 65 lines or chains with the catching apparatus

irrespective of the lateral sway of the moving car.

Also, whatever stress is imposed on the apparatus in the transfer of a bag held thereby, is imposed in such a manner that its tendency is to swing the car apparatus into the car. 70

Having described my improvements, I claim as new and desire to protect by Letters Patent of the United States:—

1. In a car apparatus of the character described, the combination of extendible arms, upright supporting means for the said arms, revoluble shafts for the said supporting means, a gear mounted upon one of the said shafts, a second gear meshing with the first mentioned gear, a pivotally mounted fluid compression cylinder, piston and connecting rod, a lever mounted upon the remaining shaft, a lever secured to the said second gear, 80 and connecting means between the said levers. 85

2. In a car apparatus of the character described, the combination of extendible arms, upright supporting means for the said arms, revoluble shafts for the said supporting 90 means, a pivotally mounted fluid compression cylinder, piston, and connecting rod, and mechanical means for operating the said piston in the said cylinder and rotating the said revoluble shafts simultaneously in opposite directions of rotation. 95

3. In a car apparatus of the character described, the combination of extendible arms, upright supporting means for the said arms, revoluble shafts for the said upright 100 supporting means, a pivotally mounted fluid compression cylinder, piston, and connecting rod, mechanical connections for operating the said piston in the said cylinder during movement of the said arms and rotating the said revoluble shafts simultaneously in opposite directions of rotation; and a spring co-operating with the said mechanical connections for compressing the fluid within the said cylinder and for controlling the 110 movement of the said arms. 105

4. In a car apparatus of the character described, the combination of extendible arms, an upright detachable socketed standard for supporting the said arms, revoluble stub 115 shafts mounted at either side of the car doorway and extending through the car floor for receiving the said standard, and pivoted upper supporting means for the said standard.

5. In a car apparatus of the character described, the combination of extendible arms, upright supporting means for the arms, revoluble shafts for the said supporting means, means for rotating the said shafts 125 simultaneously, a gear mounted upon one of the said revoluble shafts, a second gear meshing therewith; and a shaft and hand lever for actuating the said second gear.

6. In combination with flexible mail bag 130

- suspending and retaining members, a supporting and releasing device therefor consisting of a bifurcated plate member having split or forked ends and a curvilinear 5 socket-like recess; a curved spring member adapted to seat within the said recess and having its ends mounted in said forked ends and so formed as to provide a restricted compressible passage from the said recess.
- 10 7. In a car apparatus of the character described, the combination of extendible arms, upright supporting means for the arms, revoluble shafts for said supporting means disposed at either side of the car door, means 15 for rotating said revoluble shafts simultaneously in opposite directions of rotation, and a shock absorbing means connected to and adapted to coöperate with said rotating means.
- 20 8. In a device of the character described, the combination of extendible arms, companion revoluble upright supporting means for the arms, means for rotating said upright supporting means simultaneously in 25 opposite directions of rotation, a shock absorbing means connected to and adapted

to coöperate with said rotating means, and a spring also adapted to coöperate with said rotating means to retain said extendible arms in inoperative position. 30

9. In a device of the character described, the combination of extendible mail bag supporting arms, a revoluble upright standard for said arms, and fluid compression and spring controlled shock absorbing 35 means adapted to coöperate with the movement of said arms, said means comprising a swinging cylinder supporting member fixedly mounted upon said standard, a compression cylinder having one end pivotally 40 supported by said supporting member, a piston and connecting rod for the cylinder the outer end of said rod being connected to a retaining means, and tensioning means adapted to exert tension in opposition to the 45 resistance of said cylinder and piston to balance the action thereof and to return and retain said bag supporting arms in non-extended or inoperative position.

In testimony whereof I affix my signature. 50

HERBERT E. SMITH.
